His Attorney.

UNITED STATES PATENT OFFICE

2,191,328

FLOW CONTROLLING DEVICE FOR
REFRIGERATING SYSTEMSChristian Steenstrup, Schenectady, N. Y., as
signor to General Electric Company, a corpora-
tion of New York

Application April 1, 1937, Serial No. 134,325

6 Claims. (Cl. 62—116)

My invention relates to refrigerating systems of the type having a valve or flow controlling device for the purpose of admitting refrigerant to the low pressure side of the system from the high pressure side thereof.

In connection with refrigerating systems adapted to cool a compartment, such as a domestic refrigerator, an evaporator which is supplied with refrigerant from some external source is ordinarily placed within the compartment. It is necessary to provide a device for controlling the flow of refrigerant to the evaporator, such as a valve or the like, which maintains the necessary difference of pressure between the evaporator and the source of refrigerant supply. When the refrigerant passes from the high pressure side to the low pressure side of this valve, a portion of the refrigerant vaporizes due to the sudden change in pressure to which it is subjected and absorbs heat which lowers the temperature of the valve seat and the cooperating movable valve element. Any slight trace of moisture present in the refrigerant is frozen upon coming into contact with the cold surfaces of the valve seat and the cooperating valve element, causing deposits of frost to become attached thereto. This accumulation of frost on the valve seat and the cooperating valve element impairs the operation of the valve and prevents the refrigerating system from producing refrigeration.

It is an object of my invention to provide an improved refrigerating system having an arrangement utilizing heat in a compartment cooled by the system for preventing accumulation of frost in the interior of a refrigerant flow controlling device employed in the system.

Another object of my invention is to provide an improved refrigerant flow controlling device of the above character having an arrangement utilizing heat for preventing accumulation of frost on a valve element in the device, the device being so constructed and arranged that heat flow to other parts of the device operated at a lower temperature is substantially prevented.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a side elevation of a refrigerator cabinet incorporating a refrigerating system embodying my invention; Fig. 2 is an en-

larged sectional elevation of a refrigerant flow controlling device employed in the refrigerating system shown in Fig. 1; and Fig. 3 is a sectional view along the line 3—3 of the float controlling device shown in Fig. 2, showing the arrangement of a finned structure carried by the device.

Referring to the drawing in Fig. 1, I have shown the upper portion of a heat insulated refrigerator cabinet 10 of the household type having a food storage compartment 11 provided with a removable top wall 12, the compartment being cooled by a refrigerating system such as a unitary refrigerating machine. The refrigerating machine is mounted on the removable top wall 12 and includes a cooling unit or evaporator 13 attached to the inner liner 14 of the removable top wall 12, which is arranged to cool the compartment 11 disposed below the removable top wall 12 and also to make ice or freeze other articles placed within the evaporator. The machine also includes a motor and a compressor arranged within an enclosing casing 15 mounted on the top wall 12. Gaseous refrigerant is compressed by the compressor in the enclosing casing 15 and discharged into an air cooled condenser 16 of the natural draft type supported about the enclosing casing 15 upon an annulus of fins. The compressed refrigerant in passing through the condenser 16 is cooled and condensed into a liquid and then flows through a conduit 17 into a float valve chamber 18 which is mounted in the removable top wall 12 and embedded in heat insulation 19. The liquid refrigerant accumulates in the float valve chamber 18 and actuates a float 20 therein to control the flow of liquid refrigerant through a conduit 21 into the evaporator 13. The liquid refrigerant in the evaporator 13 is vaporized due to the absorption of heat in the compartment 11 and then withdrawn from the evaporator by the compressor through a conduit 22, a heat exchange device 23, and a conduit 24 extending through the bottom wall of the enclosing casing 15. This cycle of operation is continuously repeated during the operation of the machine until the compartment 11 is cooled to the desired temperature.

The construction of the float valve is best shown in Fig. 2. The float valve chamber 18 comprises a cup-shaped receptacle 25 and an inverted cup-shaped top 26 secured thereto. The receptacle 25 is welded in a flanged opening in a metal outer wall 27 of the removable top wall 12, as indicated at 28, and is embedded in the heat insulation 19 arranged between the metal outer wall 27 and the inner liner 14 of the re-

movable top wall 12. A conduit 29 is secured in an opening in the bottom wall of the receptacle 25 and extends downwardly therefrom through the heat insulation 19 and the inner liner 14 into the upper portion of the compartment 11. A valve 30 for controlling the supply of refrigerant to the evaporator 13 through the conduit 21 is arranged in the conduit 29 adjacent the lower end thereof. The valve 30 includes a plug 31 provided with a passage therethrough having a seat 31a in the upper surface thereof. An integral upstanding lug is formed on the plug 31 and a passage 32 is formed therein for guiding the movement of a valve element 33 which operates with the valve seat 31a.

The valve element 33 is controlled by the float 20 arranged in the float valve chamber 18, the float 20 being pivotally mounted at 34 upon an arm 35 which is in turn pivotally mounted at 36 upon the upper end of the conduit 29 extending into the receptacle 25. During ordinary operation, the float 20 rises and falls in accordance with variations of the level of the liquid refrigerant in the float chamber 18 and the movements of the float are transmitted to the valve element 33 by a link 37 pivotally connected between the arm 35 and the valve element 33 at 38 and 39, respectively.

It will be understood that the float chamber 18 is subject to the high temperature and pressure in the condenser 16 of the refrigerating system and that the evaporator 13 is maintained at a low temperature and pressure by the compressor so that the liquid refrigerant in the evaporator is vaporized at the desired rate. When the float rises, liquid refrigerant passes through the valve 30. A portion of this refrigerant is suddenly vaporized due to the reduction in pressure to which it is subjected, and absorbs heat which lowers the temperature of the valve seat 31a and the cooperating valve element 33. Any slight trace of moisture present in the refrigerant will be frozen upon coming into contact with the cold surfaces of the valve seat and the cooperating valve element, causing deposits of frost to accumulate thereon. In order to prevent accumulation of frost upon the valve seat 31a and the cooperating valve element 33 and the resulting impaired operation of the valve 30, a fin structure 40 is disposed about the lower end of the conduit 29 in which the valve 30 is arranged and in heat exchange relationship therewith. As best shown in Fig. 3, this fin structure 40 comprises a plurality of U-shaped fins 40a disposed annularly about the conduit 29 and brazed or welded thereto. Also a fin structure 41, similar to the finned structure 40, is carried by the conduit 21 adjacent the lower end of the conduit 29, and is secured thereto in the same manner. Thus, the fin structures 40 and 41 are disposed in the vicinity of the valve 30.

The finned structures 40 and 41 are located in the upper portion of the compartment 11 adjacent the inner liner 14 of the removable top wall 12 of the cabinet 10, as the air circulated in the compartment 11 is warmest in this portion of the compartment. Heat is absorbed by the finned structure 40 and is conducted through the wall of the conduit 29 and the plug 31 to the valve seat 31a and the cooperating valve element 33. Heat is also absorbed by finned structure 41 and is conducted through the conduit 21 to the plug 31. The heat conducted to the plug 31 prevents accumulation of frost on the valve seat 31a and the cooperating valve element

33. Furthermore, as the heat absorbed by the finned structures 40 and 41 is taken from the air circulated in the compartment 11, this arrangement is effective to cool the compartment.

In refrigerating systems the efficiency increases with decrease in the temperature of the condenser and consequent decrease in the temperature of the liquefied refrigerant. The vaporized gaseous refrigerant withdrawn from the evaporator is at a temperature considerably below that of the liquid refrigerant supplied to the float valve chamber to the condenser. In order to effect a heat transfer between the cold gaseous refrigerant and the warm liquid refrigerant, the heat exchange device 23 is arranged in good thermal conducting relationship with the conduit 29. The heat exchange device 23 comprises a number of turns of a conduit 23a disposed about the conduit 29 between the float valve chamber 18 and the valve 30, the conduit 23a having substantially a square cross-section and being interposed in the low pressure side of the refrigerating system between the conduits 22 and 24.

The heat exchange device 23 effects a pre-cooling of the liquid refrigerant in the conduit 29 on the supply side of the valve 30 which improves the efficiency of the refrigerating system and is effective to minimize vaporization of the liquid refrigerant in passing through the valve 30, and the attendant production of frost on the valve seat and cooperating valve element should there be a slight trace of moisture in the refrigerant. In order to minimize the transfer of heat into the compartment 11 from the float valve chamber 18 and the warm liquid refrigerant therein, the conduit 29 and the link 37 connected to the valve element 33 are made of a material having low heat conductivity, such, for example, as the copper-nickel alloy sold under the trademark "Monel" metal. The portion of the conduit 29 between the valve 30 and the heat exchange device 23 is effective to minimize the transfer of heat from the valve to the heat exchange device due to the low heat conductivity of this conduit.

During operation of the refrigerating system illustrated, the liquid refrigerant supplied by the condenser 16 accumulates within the float valve chamber 18 as it is liquefied. If the valve element 33 occupies the position relative to the valve seat 31a shown in Fig. 2, liquid refrigerant will flow from the float valve chamber 18 through the conduit 29 and the valve 30 until sufficient refrigerant has passed to permit the float 20 to drop and close the valve 30. As the liquid refrigerant flows through the conduit 29 it is cooled by the heat exchange device 23 to substantially the temperature of the valve 30. As the liquid refrigerant passes through the valve 30 to be supplied to the evaporator 13, a portion of the liquid refrigerant is vaporized which tends to lower the temperature of the valve seat 31a and the cooperating valve element 33. However, sufficient heat is absorbed by the finned structures 40 and 41 in the compartment 11 and conducted to the valve 30 to prevent the temperature of the surfaces of the valve seat and the cooperating valve element from being lowered to a temperature such that frost will accumulate therein should there be a slight trace of moisture in the refrigerant.

Although I have shown and described my invention in connection with a refrigerating system of the mechanical type, it will be understood that it is also applicable in connection with other

refrigerating systems and I do not, therefore, desire my invention to be limited to the particular construction shown and described, and I intend in the appended claims to cover all modifications within the spirit and scope of my invention.

What I claim as new and desire to secure by Letters Patent of the United States is:

- 5 1. A refrigerating system including a compartment to be cooled, an evaporator thermally associated with said compartment, a flow controlling device in said compartment, means for supplying refrigerant to said evaporator through said flow controlling device, and means in the vicinity of said flow controlling device supplying heat to said flow controlling device for preventing accumulation of frost therein.
- 10 2. A refrigerating system including a compartment to be cooled, an evaporator thermally associated with said compartment, a flow controlling device in said compartment, means for supplying refrigerant to said evaporator through said flow controlling device, and means including a finned structure carried by said flow controlling device in heat exchange relationship therewith for preventing accumulation of frost in said flow controlling device, said last-mentioned means utilizing heat conducted to said flow controlling device from the interior of said compartment.
- 15 3. A refrigerating system including a compartment to be cooled, an evaporator thermally associated with said compartment, a valve in said compartment, means for supplying refrigerant to said valve, means including a conduit for conducting refrigerant to said evaporator from said valve, and means including a finned structure arranged in heat exchange relationship with said valve and a second finned structure arranged in heat exchange relationship with said conduit adjacent said valve for preventing accumulation
- 20 of frost in said valve, said last-mentioned means utilizing heat conducted to said valve from the interior of said compartment.
- 25 4. A refrigerating system including a compartment to be cooled, an evaporator thermally associated with said compartment, a flow controlling device in said compartment, means for supplying refrigerant to said evaporator through said flow controlling device and for maintaining a body of liquid refrigerant on the supply side 10 of said flow controlling device, means for cooling a portion of said body of liquid refrigerant, means in the vicinity of said flow controlling device supplying heat to said flow controlling device for preventing accumulation of frost therein, and means of low heat conductivity for conducting refrigerant from said body of liquid refrigerant to said flow controlling device.
- 30 5. A flow controlling device for a refrigerating system comprising a float chamber having a float therein, a conduit extending from said float chamber, a valve in said conduit remote from said float chamber, means utilizing the movement of said float for controlling said valve, and a finned structure carried by said conduit in heat exchange relationship with said valve.
- 35 6. A flow controlling device for a refrigerating system comprising a float chamber having a float therein, a conduit extending from said float chamber, a valve in said conduit remote from said float chamber, means utilizing the movement of said float for controlling said valve, a second conduit communicating with said valve, a finned structure carried by said first mentioned conduit in heat exchange relationship with said valve, and a second finned structure carried by said second mentioned conduit adjacent said valve and in heat exchange relationship therewith.
